UNITED STATES PATENT OFFICE.

BENJAMIN P. HAYES, OF KANSAS CITY, MISSOURI, ASSIGNOR, BY MESNE ASSIGNMENTS, TO INTERNATIONAL ACCOUNTING MACHINE CO., OF NEW YORK, N. Y., A CORPORATION OF DELAWARE.

TRAY FOR REGISTERS AND THE LIKE.

Application filed July 22, 1920. Serial No. 398,265.

To all whom it may concern:

Be it known that I, BENJAMIN P. HAYES, a citizen of the United States, residing at Kansas City, in the county of Jackson and 5 State of Missouri, have invented certain new and useful Improvements in Trays for Registers and the like; and I do declare the following to be a full, clear, and exact description of the invention, such as will enable others skilled in the art to which it 10 appertains to make and use the same, reference being had to the accompanying drawings, and to the letters and figures of reference marked thereon, which form a part of 15 this specification.

My invention relates to a tray for accounting or like machines, of the type illustrated in Patent No. 1,340,827, issued May 18, 1920, to myself and Frank D. Laughlin, 20 and has for its principal object to provide a simple, substantial, and inexpensive drawer section, including the individual customer's tray, the present invention being limited to improvements in details in structure, the preferred forms of which are illustrated in the accompanying drawings, 25 wherein:

Fig. 1 is a perspective view of a tray constructed in accordance with my invention, 30 the separate elements of the tray being disconnected and spaced to better illustrate their mechanical construction and method of assemblage.

Fig. 2 is a perspective view of an assembled tray also including a scissor lever control, some of the compartment covers being removed for better illustration.

Fig. 3 is a vertical section on the line 3—3 in Fig. 2.

Fig. 4 is an enlarged detail perspective view of a portion of the tray, particularly illustrating the latch mechanism for the compartment cover.

Referring more in detail to the drawings:

The tray 1 is preferably constructed of 45 sheet metal and has front and end walls 2, 3, formed by turning up the edges of the sheet to form heads, which are reinforced by lapping the turned-up portions about a metal bar 4 to stiffen and strengthen the enclosing walls. The rear wall of each tray 50 is formed by a stamped member 5, Z-shaped in cross section to form top and bottom strips 6, 7, the bottom strip having spaced pairs of apertures 8 adapted for receiving 55 the tongues 9 that are punched from the bottom of the tray 1 and are adapted to fold over the top of the strip 7 to retain the back wall securely in place at the rear of the tray. The upper corner of the wall 60 member 5 has down-struck portions 10, forming hinge seats, each end of a down-struck section being exposed to a slot 11 and each of said sections having a center slot 12 whereby hinge pins may be positioned to carry the compartment covers (presently described) and to receive the 65 cover springs.

Each of the trays is divided into separate compartments for containing the charge 70 slips of individual customers, by rails 13 (Fig. 2), also preferably constructed of sheet metal, and comprising upstanding body portions and base flanges 14, the latter seating on the bottom of the tray and being held in place by tongues 15 punched from the tray bottom in pairs to overlie opposite rail flanges.

Each compartment has an individual cover 16 provided with hinge beads 17 and 80 a slot 18 at its transverse center.

In assembling a compartment cover the hinge beads are located on a down-struck seat of the back wall and have a pin 19 projected through an end slot 11 and 85 through the beads, the length of the pin being such that its ends nest under the angles of the upper corner of the wall to anchor the pin in place, one of the end covers being first positioned and then the remaining 90 covers positioned successively, so that when the assembly is complete the hinge pins abut throughout the length of the tray. While covers are being assembled on the end wall, the pins are also projected through 95 the hub portions 21 of springs 22, one arm of each of which bears against the end face of its cover and the opposite end against the bottom of the top strip of the back wall to urge the cover to open position (Fig. 100 2). The covers are held closed by latches 23 (Fig. 4), the base ends of which are attached to the bottom of the tray adjacent the front wall thereof by tongue and groove connection 24 and the spring arm 25, which has a lip 26 adapted to overlie the front 105 end of its cover, preferably seating in a socket 27 at the front of the cover, so that the body of the cover may lie in substantially a horizontal plane and afford a maxi- 110

mum capacity for the charge slip compartment. The plane of the covers is preferably slightly below that of the top edges of the tray, in order to avoid interference when 5 the tray is opened and closed, this arrangement being effected by bending the rear ends of the covers immediately in front of the hinges.

As the tray-operating mechanism forms 10 no part of the present invention, I will not describe the same in detail, reference being made to the patent heretofore mentioned for an understanding of the construction and mode of operation of such parts.

15 Having thus described my invention, what I claim as new therein and desire to secure by Letters Patent is:—

1. A tray comprising a bottom plate having upturned edges forming enclosing walls 20 and comprising spaced sets of paired, in- struck tongues, partition rails seated on the bottom plate between paired tongues, comprising body portions and oppositely di- rected bottom flanges, the tongues turned 25 onto the flanges to hold the rails in place.

2. A tray comprising a bottom plate having upturned edges forming enclosing walls 30 and comprising spaced sets of paired, in- struck tongues, partition rails seated on the bottom plate between paired tongues, comprising body portions and oppositely di- rected bottom flanges, the tongues turned 35 onto the flanges to hold the rails in place, a rear wall member, and covers hinged to the rear wall members covering the compartments formed by said partition rails.

3. A tray comprising a rear wall, having an upper, forward corner slotted and in- 40 dented to form a hinge seat, a cover having a hinge member located on said seat, and a pin located in said hinge member, with its ends pocketed in the angle of upstanding portions of the corner.

4. A tray comprising a rear wall, having an upper, forward corner slotted and in- 45 dented to form a hinge seat, a cover having a hinge member located on said seat, and a pin located in said hinge member, with its ends pocketed in the angle of upstanding 50 portions of the corner, a spring urging the cover to open position, and a latch at the front of the tray for retaining the cover against the tension of said spring.

5. A tray comprising a rear wall, having an upper, forward corner slotted and in- 55 dented to form a hinge seat, a cover having a hinge member located on said seat, and a pin located in said hinge member, with its ends pocketed in the angle of upstanding 60 portions of the corner, the cover having a latch socket at its forward, free edge, and a flexible latch at the front of the tray, having a lip engageable with the cover within the latch socket.

6. A tray comprising a bottom plate hav- 65 ing a rear longitudinal series of tongues and spaced transverse sets of paired tongues, a rear wall member, Z-shaped in cross section, the bottom strip of the wall seating on the bottom of the tray and having apertures re- ceiving the longitudinal tongues to anchor 70 the strip, the upper corner of the wall being slotted and indented between the sets of transverse tongues to form hinge seats, rails seated on the tray bottom between the 75 paired ear sets and anchored thereby, covers having hinge members located on said hinge seats, pins in the hinge members having ends pocketed beneath the angle of upstanding portions of the corner of the rear wall, 80 springs on said pins engaging the covers and the upper strip of the rear wall, and latches at the front of the tray for retaining the covers against the tension of said springs.

In testimony whereof I affix my signature. 85
BENJAMIN P. HAYES.
